UNITED STATES PATENT OFFICE.

WILLIAM AKIN, OF LOS ANGELES, CALIFORNIA.

GAS HEATER AND COOKER.

No. 910,345.

Specification of Letters Patent.

Patented Jan. 19, 1909.

Application filed April 20, 1908. Serial No. 428,289.

To all whom it may concern:

Be it known that I, WILLIAM AKIN, a citizen of the United States, residing at Los Angeles, in the county of Los Angeles and State 5 of California, have invented a new and useful Gas Heater and Cooker, of which the following is a specification.

This invention relates to a device adapted to be used for heating rooms or for cooking 10 purposes and one important object of the invention is to prevent the heat from rising upward from the burner, and to cause the heat to be radiated in all directions laterally from the burner so that the heat is diffused and 15 radiated over a large area of the room, when the device is used as a heater.

Another object is to obviate dryness of the air by supplying moisture thereto and to prevent too rapid evaporation of the water which 20 furnishes the moisture so that a given amount will last a long time without requiring renewal.

Another object is to provide for regulating the position of the water supply and to there- 25 by control the rate of evaporation.

Another object is to so construct the device that it may be applied to and supported by a gas fixture, or may be supported by its own frame in any position on a table or the 30 floor and connected by a flexible hose with the gas supply.

The accompanying drawings illustrate the invention, and referring thereto:—Figure 1 is a vertical cross section on line $x^1 x^1$, Fig. 2. 35 Fig. 2 is a longitudinal cross section on line $x^2 - x^2$ Fig. 1. Fig. 3 is a plan view in detail, of the device for detachably securing the spreader. Fig. 4 is a vertical cross section through the device as applied to a gas fixture. 40

Referring to Figs. 1 and 2, the standard comprises three legs 1 which are united and braced at an intermediate point by a ring 2, and being secured at the top to a ring 3. A 45 bar 4 extends diametrically across the standard, being secured at one end to a leg 1 and the ring 2, and at its other end to the ring 2. A strap 5 is screwed to one side of the center part of bar 4 and the bar 4 and strap 5 are 50 bowed out at 6, each for a half circle, so that a circular hole is formed in which is clamped a vertical pipe 7, the lower end of which has a valve 8 which is connected by a hose 9 through which the gas is supplied. Screwed 55 to the upper end of the pipe 7 is a burner 10 having orifices 11 from which the flame is-

sues. The burner may be readily unscrewed from the pipe 7 whenever desired. The upper end of the burner comprises a cap 12 which is removable. The upper ends 13 of 60 legs 1 are formed with hooks 14 which support the rim of a dished spreader 15 having a cupped central portion 16 which rests on top of the burner cap 12. Above the spreader 15 is an upper spreader 17 having a depressed 65 cupped central portion 18 which nests in the cupped portion 16 of the lower spreader, and is formed with an annular bead 19 which rests on the flat top of the lower spreader and thus prevents the upper spreader from tipping. A screw 20 passes through the two 70 spreaders into the burner cap 12 and under the head of the screw is an elongated button or washer 21 which clamps the spreaders securely in place. 75

The upper spreader has an elongated opening 22 a trifle larger than the washer 21 so that by turning the upper spreader and bringing the opening 22 into register with the washer 21 the spreader may be lifted off. 80 This fastening device enables ready attachment or detachment of the spreaders. A cone 23 is removably seated on the upper spreader 17 and hides the fastening device, the latter being readily accessible upon lifting the cone. A disk 24 of asbestos is arranged below the cone 23 and effectively aids in preventing the heat from passing upwardly. The rim of the lower spreader is supported by the hooks of the frame so that 85 the spreader is held firmly in position against tipping and relieves the burner from its weight so that heavy dishes or flat irons may be heated on the lower spreader whenever desired. The upper spreader 17 is supported 90 sufficiently above the lower spreader to form an air space between them which is a most important feature in preventing the upward passage of heat. The flame issuing from the burner is spread laterally by the lower 100 spreader and thrown out radially into the room thereby diffusing the heat uniformly throughout a large area. I have found in practice that best results are obtained by arranging the rims of both spreaders in the 105 same horizontal plane.

A water pan 25 is adjustably supported on the pipe 7 by a tube 26 which is secured to the bottom of the pan, the tube being slideable on the pipe 7 to bring the pan to the 110 desired height below the burner and to thus regulate the rate of evaporation. A thumb

screw 27 passes through a collar 28 and through the upper end of the tube to clamp the tube to the pipe and thus adjustably hold the pan 25 in the desired position. The pan 5 in its lowest position rests on the upper edge of the cross bar 4. The pan has an upper inwardly directed flange 29 which serves to prevent water from splashing out when the heater is removed. During the operation of 10 the burner the water evaporates slowly from the pan due to its location at such a considerable distance below the burner and thus the water does not have to be renewed frequently, while it evaporates sufficiently fast 15 to produce the necessary amount of moisture. The water pan keeps heat from the floor or table and prevents downward radiation of heat which would damage the floor covering or table. It also protects the flexible tube from the action of heat.

When the device is to be used for cooking the upper spreader 17 is removed, as before described, which exposes the flat upper surface of the lower cone 15 upon which the 25 dishes may be placed. The lower spreader 15 is of course very hot and the heat passes therethrough to the things being cooked. By simply unscrewing the lower end of the 30 burner from the pipe 7, the burner and spreaders carried thereby may be lifted bodily from the standard and the burner may be screwed to the tip of a gas fixture 30 as indicated in Fig. 3. Obviously when thus applied the upper spreader 17 may be used or 35 not, according to whether it is desired to heat the room or to cook. The upper ring 3 has a greater diameter than the upper spreader 17 and lying outside thereof acts as a guard to prevent persons or their garments coming 40 into contact with the hot rim of the spreader.

What I claim is:—

1. A gas heater and cooker comprising a burner the lower end of which is adapted to be fitted to a gas fixture or gas supply, a 45 dished spreader having a cupped center on the top of the burner, another dished spreader above the first spreader and having a cupped portion nesting with that of the first spreader and having an annular bead 50 resting on top of the first spreader.

2. A gas heater and cooker comprising a burner the lower end of which is adapted to be fitted to a gas fixture or gas supply, a dished spreader having a cupped center on 55 the top of the burner, another dished spreader above the first spreader and having a cupped portion nesting with that of the first spreader and having an annular bead resting on top of the first spreader, a disk of 60 asbestos above the cupped portion of the upper spreader, and a removable cone on the upper spreader over the asbestos.

3. A gas heater and cooker comprising a burner the lower end of which is adapted to 65 be fitted to a gas fixture or gas supply, a

spreader above the burner, another spreader above the first spreader forming an air space to prevent upward passage of heat, a screw in the cap of the burner, the upper spreader having an elongated slot, and an elongated 70 washer under the head of the screw above the spreader.

4. A gas heater and cooker comprising a burner the lower end of which is adapted to be fitted to a gas fixture or gas supply, a 75 dished spreader having a cupped center on the top of the burner, another dished spreader above the first spreader and having a cupped portion nesting with that of the first spreader and having an annular bead 80 resting on top of the first spreader, a screw in the cap of the burner, the upper spreader having an elongated slot, and an elongated washer under the head of the screw above the spreader.

5. A gas heater and cooker comprising a burner the lower end of which is adapted to be fitted to a gas fixture or gas supply, a spreader above the burner, and another spreader above the first spreader forming an 90 air space to prevent upward passage of heat, a frame comprising a plurality of legs the upper ends of which are formed with hooks in which the rim of the lower spreader rests, an upper ring uniting the legs, and a lower 95 ring uniting the legs.

6. A gas heater and cooker comprising a burner the lower end of which is adapted to be fitted to a gas fixture or gas supply, a spreader above the burner, another spreader 100 above the first spreader forming an air space to prevent upward passage of heat, a frame comprising a plurality of legs the upper ends of which are formed with hooks in which the rim of the lower spreader rests, an upper ring 105 uniting the legs, a lower ring uniting the legs, a cross bar extending across the lower ring, and a water pan above the cross bar.

7. A gas heater and cooker comprising a burner the lower end of which is adapted to 110 be fitted to a gas fixture or gas supply, a spreader above the burner, another spreader above the first spreader forming an air space to prevent upward passage of heat, a frame comprising a plurality of legs the upper ends 115 of which are formed with hooks in which the rim of the lower spreader rests, an upper ring uniting the legs, a lower ring uniting the legs, a cross bar extending across the lower ring, a water pan above the cross bar, a strap secured to the cross bar, and a gas pipe extending up between the cross bar and strap and screwed to the burner.

8. A gas heater and cooker comprising a burner the lower end of which is adapted to 125 be fitted to a gas fixture or gas supply, a spreader above the burner, another spreader above the first spreader forming an air space to prevent upward passage of heat, a frame comprising a plurality of legs the upper ends 130

of which are formed with hooks in which the
5 rim of the lower spreader rests, an upper ring
uniting the legs, a lower ring uniting the legs,
a cross bar extending across the lower ring, a
water pan above the cross bar, a strap se-
cured to the cross bar, a gas pipe extending
10 up between the cross bar and strap and
screwed to the burner, the water pan having
a central tube and being adjustable vertically
15 on the gas pipe, and a thumb screw for
clamping the tube and holding the pan in the
desired position on the gas tube.

9. A gas heater and cooker comprising a
burner the lower end of which is adapted to
15 be fitted to a gas fixture or gas supply, a
spreader above the burner, another spreader
above the first spreader forming an air space
to prevent upward passage of heat, a frame
20 comprising a plurality of legs, the upper ends
of which are formed with hooks in which the
rim of the lower spreader rests, an upper ring
uniting the legs, a lower ring uniting the legs,
a cross bar extending across the lower ring,
25 and a water pan above the cross bar, the
water pan having an upper inwardly directed
flange.

10. A gas heater and cooker comprising a
burner the lower end of which is adapted to

be fitted to a gas fixture or gas supply, a
spreader above the burner, and another 30
spreader above the first spreader forming an
air space to prevent upward passage of heat,
the lower spreader having a flat top and the
upper spreader being removable to enable
dishes to be placed on the flat top of the 35
lower spreader for cooking.

11. A gas heater and cooker comprising a
burner the lower end of which is adapted to
be fitted to a gas fixture or gas supply, a
spreader above the burner, another spreader 40
above the first spreader forming an air space
to prevent upward passage of heat, the lower
spreader having a flat top and the upper
spreader being removable to enable dishes to
be placed on the flat top of the lower spreader 45
for cooking, a frame supporting the spreaders,
and a ring at the upper part of the frame hav-
ing a greater diameter than the spreaders
and acting as a guard therefor.

In testimony whereof, I, have hereunto set 50
my hand at Los Angeles, California, this 13th
day of April, 1908.

WILLIAM AKIN.
